TRAY FOR PRODUCTION PARTS

Godfrey L. de'Caccia, 535 E. Adams St.,
Long Beach, Calif.

Filed June 18, 1962, Ser. No. 70,569

Term of patent 14 years

(Cl. D58—13)

FIG. 1.

FIG. 2.

FIG. 5.

FIG. 3.

FIG. 6.

FIG. 4.

FIG. 1 is a perspective view of a tray for production parts showing my new design;

FIG. 2 is a top plan view thereof;

FIG. 3 is a front elevation thereof;

FIG. 4 is a bottom plan view thereof;

FIG. 5 is an end elevation thereof; and

FIG. 6 is a rear elevation thereof.

I claim:

The ornamental design for a tray for production parts, as shown.
